TWISTING SPINDLE BALLOON CONTROL
 Alfred W. Vibber, 290 Churchill Road, West Englewood,
 Teaneck, N.J.
 Filed Dec. 17, 1963, Ser. No. 331,149
 7 Claims. (Cl. 57—106)

This invention relates to an apparatus for twisting and/or plying strands, and more particularly relates to an improved self-adjusting apex guide for such apparatus.

This application is a continuation-in-part of application Serial No. 261,704, filed December 14, 1951, now abandoned, and of application Serial No. 4,973, filed January 27, 1960.

The self-adjusting apex guide of the present invention is shown herein in connection with its use in a strand plying apparatus such as that disclosed and claimed in applicant's prior application Serial No. 275,016, filed April 24, 1963, now Patent No. 3,153,895. In such apparatus a first strand is pulled forwardly through a balloon, formed as by a driven balloon creating flyer, about a supply package of a second strand, the first strand meeting the second strand at a plying point axially of and beyond balloon. The control of the tension in the ballooning strand to maintain it substantially constant is of primary importance if the plied cord is to have both the strands therein of equal length. Various means have been proposed for automatically controlling the size of the balloon, and thus the tension of the strand therein, to compensate for variations in tension arising from variations in balloon size. Among such devices are those shown in Clarkson Patent No. 2,689,449, and in applicant's above recited applications of which this application is a continuation-in-part, wherein the guide for the apex of the balloon is made to be self-adjusting. The present invention represents an improvement upon such former adjustable apex guides in that it is more sensitive, more compact, and more easily adjusted.

The invention has among its objects the provision of a novel improved self-adjusting apex guide for a strand twisting and/or plying spindle.

Another object of the invention lies in the provision of a self-adjusting apex guide adapted for use as indicated, such guide possessing high sensitivity in spite of the fact that it may be made to engage the ballooning strand only at a location closely adjacent the apex of the balloon.

Still another object of the invention is the provision of a self-adjusting apex guide wherein an anti-friction bearing is employed both to support the guide and to function as a speed reducing gearing mechanism interposed in the drive train of the apex guide adjusting mechanism.

A further object of the invention is the provision of a self-adjusting apex guide which may readily be adjusted while it is in operation both to vary its distance from the balloon creating flyer of the spindle and to vary the resilient biasing force opposed upon the guide in a direction opposite the direction of rotation of the balloon.

The above and further objects and novel features of the invention will more fully appear from the following description when the same is read in connection with the accompanying drawings. It is to be expressly understood, however, that the drawings are for the purpose of illustration only, and are not intended as a definition of the limits of the invention.

In the drawings, wherein like reference characters refer to like parts throughout the several views,

FIG. 1 is a fragmentary view in side elevation of a spindle of the skip type for plying strands together, such spindle incorporating a first embodiment of self-adjusting apex guide in accordance with the invention;

FIG. 2 is a view in vertical section on an enlarged scale of the embodiment of self-adjusting apex guide

2

mechanism employed in the apparatus of FIG. 1, the section being taken along the broken line 2—2 of FIG. 3;

FIG. 3 is a view in horizontal section through such first embodiment of apex guide, the section being taken along the line 3—3 of FIG. 2; and

FIG. 4 is a view in vertical axial section through a second embodiment of self-adjusting apex guide in accordance with the invention.

Although the self-adjusting apex guide of the present invention is shown herein in connection with its use in a strand plying spindle of the skip type, it is to be understood that such guide may be used in a variety of spindles of other types such as singles, uptwisters, and downtwisters, wherein it is desired accurately to control the size of the balloon and thus the tension of the strand therein.

Turning now to FIG. 1, the plying spindle there shown is generally designated by the reference character 10. Spindle 10 has a vertically disposed centrally hollow main shaft 11 which is rotatably mounted in a suitable bearing in a housing 16 affixed to a supporting frame 12. The shaft 11 is driven by a belt 14 entrained over a pulley 15 affixed to shaft 11, the belt being driven by a suitable power source such as an electric motor, not shown. Supported on shaft 11 by a bearing contained in a housing 19 is a support 17 which is held from rotation by pairs of coaxing lower and upper magnets 20 and 21 mounted on housings 16 and 19, respectively.

30 A package support 22 is mounted on support 17, support 22 having means for holding a strand package 24 centrally thereon. Package 24, which supplies the inner strand *b*, is surrounded by a cage-like guard 23, a part of which also functions to tension the strand *b* preliminarily in the travel of such strand downwardly to a guide pulley 25 mounted on support 17. The spindle 10 as thus far described is generally similar to that shown and described in Clarkson Patent No. 2,689,449.

35 The strand handling device 26 on support 17 of the present apparatus is an idle strand tensioning means which is preferably adjustable to vary its strand tensioning effect. The tensioning device 26 shown is generally similar to that shown in FIG. 5 of the patent to Klein, No. 2,671,305, changed as to its orientation and the manner of feeding the strand into and away from the tension device. It is to be understood that other known strand tensioning devices may, if desired, be substituted for the tensioning device 26 here shown and described.

40 The strand *b*, after passing under guide pulley 25, travels to the right (FIG. 1) initially to contact the right hand roller 27 at the bottom thereof, and then travels counter-clockwise around the roller to contact the left hand roller 29 adjacent the bottom thereof. The strand then travels clockwise around roller 29 and between such roller and an adjustably tensioned leaf spring 30 which has a curved free end overlying and conforming to the curvature of the roller 29. As set forth in the above Klein patent, the ends of the shafts mounting rollers 27 and 29 are supported in guideways (not here shown) which lie generally parallel to the direction of the runs of the strand 45

50 approaching roller 27 and leaving roller 29, the tension in the strand and the force exerted on the roller 29 through strand *b* by the leaf spring 30 causing the strand to be nipped forcibly between the rollers. The leaf spring 30 is secured at its upper end to support 17; 55 the spring is adjustably thrust toward roller 29 by a set screw threaded into a bracket affixed to support 17.

55 From the top of roller 29 the strand *b* travels to the right to a roll guide set 31, and thence progresses to a canted fixedly journaled guide roll 32 which directs it 60 downwardly centrally into the open upper end of the hollow main shaft 11 of the spindle. Strand *b* is pulled

downwardly through the bore in shaft 11 to meet and be plied with a second strand *a* at a plying point X within the shaft.

The strand *a* is supplied by an outer strand package 34 mounted on a fixed package support having a central package receiving member 35. From package 34, after being preliminarily tensioned by means not shown, the strand *a* proceeds to a capstan set 36 which feeds it forward at substantially constant speed. Capstan set 36 may be constructed and driven in the same manner as the capstan for feeding the strand there designated *b* in FIG. 8 of Clarkson Patent No. 2,729,051. Capstan set 36 of the present apparatus has two vertically spaced rollers 37, 39, both driven at a constant speed from and in synchronism with shaft 11, the lower roller 39 being tipped at a small angle, as shown. Strand *a* travels about rollers 37, 39 a plurality of times in laterally spaced wraps, passing between roll 37 and a spring pressed idle roll 40, and then leaves the capstan set at the bottom of roller 39 to travel about a fixedly mounted guide pulley 41. From pulley 41 the strand proceeds upwardly to a further fixedly mounted guide pulley 42 which is mounted on a cross arm 44 secured to a fixed standard 45 rising from frame 12. From pulley 42 the strand travels to a further pulley 46, journaled on a bracket 47 affixed to cross arm 44, from which it proceeds downwardly to an apex guide device 49 for the balloon 50 formed in strand *a* by the spindle.

The device 49 here shown is the first embodiment of balloon control device in accordance with the present invention. Such device 49 includes torque responsive means in engagement with the upper end of the balloon for sensing changes in the diameter of the balloon, and novel means responsive to the first named means for changing the size of the balloon.

The strand *a* travels downwardly from pulley 46 to a vertically adjustable apex guide and balloon engaging means, which is a part of the balloon control device 49 to be described, and thus into the balloon 50 formed in the strand by a flyer disc 51 fixedly secured to shaft 11. Disc 51 has a strand guiding eye adjacent its edge, the strand passing through such eye and thence generally radially and somewhat downwardly beneath the flyer disc into an opening in the side of shaft 11 in a manner similar to that shown in FIG. 6 of Clarkson Patent No. 2,729,051. Within the bore in shaft 11 generally below the radial passage through the sidewall thereof there is affixed a cord forming die (not shown) within which equal lengths of the strands *a* and *b* are wrapped about each other at the plying point X. After leaving the plying point, the now formed cord *c* travels downwardly through the bore in shaft 11, out the bottom end thereof, and downwardly to a fixedly mounted guide pulley 52.

From pulley 52 the cord *c* travels upwardly to a second capstan set 54 which is similar to the above described capstan set 36. The opposed vertically spaced rolls 55, 56 of such capstan set are driven at a constant speed from and synchronized with the shaft 11. The cord passes around rolls 55, 56 a plurality of times in laterally spaced wraps, being nipped between roll 55 and an idle roll 57 which is spring pressed toward roll 55. From the capstan set 54 the cord *c* travels downwardly at substantially constant speed to a take-up bobbin 59 which is frictionally rim-driven by one or both of its supporting rolls 60.

Turning now to FIGS. 2 and 3, the construction of the first illustrative embodiment of balloon apex guide and balloon control mechanism 49 of the present invention is shown in detail. As there shown, device 49 has a body in the form of a generally circular cylindrical barrel 61, the outer lower portion of which is threaded at 62 and is received in a threaded bore 64 adjacent the end of the cross arm 44. Body 61 is held in vertically adjusted position on the overarm by a lock nut 65 mounted on the threaded portion 62 of the body 61. Inwardly thereof of the body 61 is provided with four radially disposed inwardly

extending flanges or wings 66, the inner edges of such wings being of part-circular cylindrical shape and being threaded as shown at 67. Angularly between opposite pairs of wings 66 the body 61 is provided with diametrically aligned further flanges or wings 69, the inner edges of which are smooth and lie in vertical planes somewhat radially inwardly of the inner edges of wings 66. The described construction of the inner portion of body 61 provides for the accurate vertical guiding and adjustment of the apex guide means per se now to be described.

The apex guide in this instance is formed somewhat similarly to an anti-friction bearing having an outer race 70, an inner race 71, and a plurality of bodies of revolution 72 interposed between the races. The outer race 70, which has a diameter somewhat less than the inner diameter of opposing wings 66, is provided with two opposed vertical grooves 74 within which the inner edges of wings 69 are accurately slidably received, the respective surfaces of the inner edges of wings 69 accurately engaging the confronting corresponding lateral and radially inner surfaces of grooves 74. The outer race is, therefore, free to move vertically while being accurately guided along its axis and being held from rotation about its axis. The inner race 71 is in the form of a balloon apex guide having an inner passage 75 therethrough which is circular cylindrical at its upper portion 76 and is flared in its lower portion 77. The configuration of such bore may, for example, be the same as that of the strand engaging bore shown in FIG. 7 in each of applicant's prior applications Serial No. 261,704 and 4,973. Thus the portion 76 of the passage forms a guide for the apex of the balloon, and the portion 77 thereof presents an annular surface which engages an intermediate portion of the ballooning yarn.

The confronting edges of the outer and inner races 70 and 71 are provided with peripherally extending grooves of such shape as accurately to receive therebetween a plurality of bearing rollers 72 which in this instance are in the form of downwardly converging frustums of cones. The rollers 72 are provided with a tubular cage member 79 having a plurality of windows therethrough, each such window receiving a roller 72.

The combination of elements 70, 71, 72 function as a planetary gearing device, wherein the outer race 70 sets similarly to a ring gear, the inner race or apex guide 71 functions as a sun gear, and the rollers 72 function as planet gears. The cage member 79, which rotates about the common axis of the races, thus rotates at a reduced speed with respect to the inner race or apex guide 71, thereby yielding a desired reduction in the speed of driving of the cage member.

The elements 70, 71, 72 are supported and vertically adjusted by means of an upper tubular extension 80 of the cage member 79. Thus at the zone 81 the extension 80 of the cage member is radially thickened at a zone 81 which is externally threaded so as threadedly to interfit with the threads 67 on the inner edges of wings 66. Thus driving of the cage member 79 in one direction will cause members 70, 71, 72 as a whole to rise, and turning of the cage member in the other direction will cause them to fall. This lengthens and shortens, respectively, the effective distance between the balloon creating flyer 51 and the apex guide surface 76, and thus lengthens and shortens the balloon. It will be understood that the hand of thread 67 and that on portion 81 of the extension of the cage member 79 is such that rotation of the inner race 71 in the direction of balloon rotation lowers the apex guide and rotation of the race 71 in the opposite direction raises the apex guide.

The apex guide device 49 is provided with means in the form of a coil torque spring 82, telescoped about extension 80, which resiliently opposes the turning of the cage member 79, and thus the rotation of the apex guide member 71 in the direction of rotation of the balloon. Spring 82 has a lower tang 84 fixedly secured to the por-

tion 81 of a cage member extension 80, as shown, a tang 85 at the upper end of the spring being secured to a radially inwardly extending flange 86 of a cap member 87 mounted on body 61. The cap member 87 has a portion 89 overlying the upper end of body 61 and a downwardly extending skirt 90 which is telescoped over the upper end of body 61. The cap is retained on body 61 in the desired angular position by means of one or more set screws 91 threaded radially into skirt 90 and having an inner pilot end portion 92 received in an annular groove 94 in the outer surface of body 61. It will be apparent that the spring 82 may be initially wound, with the spindle 10 at rest, by loosening set screw 91 and turning cap 87 as required, following which the set screw is tightened. The upper surface of portion 80 of the extension 80 of the cage member will at that time engage the lower radially inner surface of part 89 of cap 87 as a stop. Further adjustment of the spring 82 can readily be carried out at any time as required, even while the twisting spindle is in operation, by suitably turning cap 87. It will also be apparent that, by reason of the threaded mounting of the body 61 in the cross arm 44, the adjustment of the apex guiding device as a whole may be easily affected, even while the apparatus is in operation, by loosening lock nut 65, turning the body 61 in the appropriate direction, and then tightening the lock nut. If desired, and as shown in the illustrative embodiment, the spring 82 may be effectively shielded from the strand *a* by extending portion 80 of the cage member 79 upwardly past portion 81 thereof in a circular cylindrical tubular extension 95 which extends upwardly beyond flange 86 of the cap member 87 and has sliding engagement therewith at zone 96.

It is thus apparent that there has been provided a balloon apex adjusting mechanism which is particularly characterized by its compactness, its ease of adjustment, and by its sensitivity, since it incorporates a speed reducing mechanism in the means which supports the apex guide per se for rotation. Friction in the device may be decreased, and the device made still more sensitive by forming the cage 79 including the portion 81 thereof of a low friction material such as "Teflon." Such material, which is particularly characterized by its low friction with various materials such as metal of which the rollers 72 may be made, possesses adequate strength and durability for the purpose at hand, particularly since the stresses encountered are relatively small.

In FIG. 4, there is shown a second embodiment of self-adjusting apex guide in accordance with the invention. Such device, which likewise combines an anti-friction bearing for the apex guide and a speed reducing mechanism in the driving train therefrom, differs from that of the first described embodiment in that it interposes a further speed reducing mechanism between the rotatable cage for the intermediate bodies of revolution (planets) of the bearing and the means for adjusting the apex guide per se toward and away from the flyer. Parts in FIG. 4 which are generally the same as those of FIGS. 1, 2 and 3 are designated by the same reference characters but with an added prime.

The adjustable apex guide of FIG. 4, which is generally designated by the reference character 49', includes a generally circular cylindrical body 61' which is threadedly mounted in threaded vertical bore 64' in the outer end of a crossarm 44', being adjustably held therein by means of a lock nut 65'. As before, the apex guide per se is in the form of an anti-friction bearing having an outer race 70' and an inner race 71', functioning as a balloon apex guide and interposed bodies of revolution 72'. Bodies 72' in this instance are shown as balls which are held in a cage 79' so as to be free for rotation about their own axes while rotating at a reduced speed with respect to the inner race 71' about the axis of the latter.

The outer race 70' is, in this instance, supported upon and held from rotation about its axis by two adjusting

70
75

screws generally designated 100, the screws 100 being located in diametral relationship on opposite sides of the axis of races 70' and 71'. The lower end of each screw 100 is threaded as shown at 101 and is received within a respective threaded bore 102 in the outer race 70'. The upper end of each screw 100 is threaded as shown at 104 with a thread of the same hand as thread 101 but of a somewhat different pitch. Thread 104 is received within a respective one of two threaded bores 105 in radially disposed arms 106 affixed to the upper end of body 61'. Intermediate the length of each screw 100 there is fixedly secured a pinion 107 having spur teeth which mesh with an elongated spur gear 109 formed upon an upper thickened portion 81' of an extension 80' of the cage member 79'. It will be apparent that as the inner race 71' turns, the cage member 79' rotates at a reduced speed. Gear 109 on the cage member extension in turn rotates the screws 100 through the pinions 107.

20 The differential action of the threads 101 and 104 of the screws 100 functions markedly to reduce the extent of vertical travel of the members 70', 71', and 72' relative to the degree of rotation of the inner race 71'. The spur teeth on the gears 107 and 109 extend vertically, so 25 pinions 107 may move vertically with respect to gear 109 as required as the screws 100 rotate. The hand of screw threads 101 and 104 is such that rotation of race 71' in the direction of balloon rotation lowers the apex guide, and rotation of the race 71' in the opposite direction raises the apex guide.

30 Rotation of the inner race 71' in the direction of rotation of the balloon is resiliently opposed by a coil torque spring 82' having a lower tang 84' secured to the top of portion 81' the extension of cage member 79' 35 and an upper tang 85 secured to the inner edge of a body portion 110 of a cap 111 which is rotatably adjustably mounted on the upper end of body 61' in the same manner as cap 74 of the first described embodiment. If desired, the spring 82' may be hooded by an extension 95' 40 of the cage member 79' in the same manner as in the first embodiment, such extension being guided at 96' by the inner edge of the portion 110 of the adjustable cap.

45 As in the first described embodiment, the friction between the relatively movable parts of device 49' of FIG. 4 may be greatly decreased by making at least some of the parts of low friction material such as "Teflon" (polytetrafluoroethylene). Thus the cage member 79', the gears 107 and 109, and the screws 100 may, if desired, be made of such material. The described device 50 may thus be made with a high sensitivity, responding rapidly to compensate for small variations in balloon diameter. Whereas the ring, sun, and planets in the disclosed embodiments of the planetary gearing device are, in effect, parts of an anti-friction bearing and function 55 as a frictional gearing device, such parts may, if desired, be provided with meshing teeth as in more conventional planetary gearing devices.

60 Although only a limited number of embodiments of the invention have been illustrated in the accompanying drawings and described in the foregoing specification, it is to be understood that various changes, such as in the relative dimensions of the parts, materials used, and the like, as well as the suggested manner of use of the apparatus of the invention, may be made therein without departing from the spirit and scope of the invention will 65 now be apparent to those skilled in the art.

What is claimed is:

1. A self-adjusting balloon apex guide comprising a planetary gearing device having a ring and parts rotatable with respect to the ring including a sun coaxial of the ring, and at least one body of revolution functioning as a planet interposed between and drivingly engaging the ring and sun, the sun being in the form of an annular member having a central strand guiding passage therethrough, means for retaining the ring from rotation

while permitting its reciprocation along the common axis of the ring and the sun, and means supporting the planetary gearing device and for adjusting it along said axis comprising means connected to the planet to rotate therewith about said axis, means connected to the last named means to drive the planetary gearing device for travel in opposite directions along said axis when the sun rotates about said axis in respective opposite directions, and resilient means connected to one of the rotatable parts of the planetary gearing device yieldingly to oppose rotation of the sun in the direction of rotation of the balloon.

2. A self-adjusting balloon apex guide comprising a planetary gearing device having a ring and parts rotatable with respect to the ring including a sun coaxial of the ring, and a plurality of bodies of revolution functioning as planets interposed between and drivingly engaging the ring and sun, the sun being in the form of an annular member having a central strand guiding passage therethrough, means for retaining the ring from rotation while permitting its reciprocation along the common axis of the ring and the sun, and means supporting the planetary gearing device and for adjusting it along said axis comprising means connected to the planets to rotate therewith about said axis, means connected to the last named means to drive the planetary gearing device for travel in opposite directions along said axis when the sun rotates about said axis in respective opposite directions, and resilient means connected to one of the rotatable parts of the planetary gearing device yieldingly to oppose rotation of the sun in the direction of rotation of the balloon.

3. A self-adjusting balloon apex guide as claimed in claim 2, comprising a support, and wherein the means driving the planetary gearing device in opposite directions along the said axis comprises first screw means on the support and second screw means, driven by the means connected to the planets to rotate therewith, engaged with said first screw means.

4. A self-adjusting balloon apex guide as claimed in

15
20
25
30

35

40

claim 3, wherein the second screw means is fixedly connected to the means connected to the planets to rotate therewith.

5. A self-adjusting balloon apex guide as claimed in claim 2, comprising a support, and wherein the means driving the planetary gearing device in opposite directions along the said axis comprises first, screw threaded, passage means on one of the support and the ring, second, screw threaded, means threadedly engaged in said threaded passage means and connected to the other of the support and the ring, and means drivingly connecting the second screw threaded means to the means connected to the planets to rotate therewith.

6. A self-adjusting balloon apex guide as claimed in claim 2, comprising a support, and wherein the means driving the planetary gearing device in opposite directions along the said axis comprises first, screw threaded passage means on the support, second, screw threaded, means threadedly engaged in said threaded passage means and connected to the ring, and means drivingly connecting the second screw threaded means to the means connected to the planets to rotate therewith.

7. A self-adjusting balloon apex guide as claimed in claim 6, wherein the second screw threaded means is in the form of at least one elongated screw shaft having threads of the same hand but of different pitch on its opposite ends, one of said ends of the shaft being threadedly engaged with the first screw threaded passage means, and wherein the ring has further screw threaded passage means therein aligned with the first screw threaded passage means, and the other end of the threaded shaft is threadedly engaged with the further screw threaded passage means in the ring.
